(57) **CLAIM**

The ornamental design for a table arch stand, as shown and described.

DESCRIPTION

FIG. 1 is a top perspective view of a table arch stand showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded front view of the table arch stand showing my new design.

The broken lines in the drawings depict portions of the table arch stand that form no part of the claimed design.
